PILOTING UNIT FOR GAUGING THE FINISH OF INTERNAL SURFACES

Frederick L. Fitts, Ann Arbor, Mich., assignor, by mesne assignments, to Micrometrical Manufacturing Company, Ann Arbor, Mich., a corporation of Delaware

Filed June 20, 1960, Ser. No. 61,022

Term of patent 14 years

(Cl. D52—6)

FIGURE 1 is a front perspective view of a piloting unit for gauging the finish of internal surfaces showing my new design.

FIGURE 2 is an end elevational view as seen from the left of FIGURE 1.

FIGURE 3 is an end elevation view as seen from the right of FIGURE 1.

FIGURE 4 is a rear elevational view.

I claim:

The ornamental design for a piloting unit for gauging the finish of internal surfaces, substantially as shown.
